TWO-PART ATTITUDE INDICATING AIRCRAFT INSTRUMENT DIAL

Paul E. Sanderson, 3108 Wilma, Wichita, Kans.

Filed July 27, 1962, Ser. No. 71,069

Term of patent 14 years

(Cl. D52—6)

Fig. 1

Fig. 2

Fig. 3

Fig. 7

FIG. 1 is a front elevational view of a two-part attitude indicating aircraft instrument dial, showing my new design.

FIG. 2 is a side elevational view thereof.

FIG. 3 is another front elevational view similar to FIG. 1, showing the dial in a different position in flight.

FIG. 4 is a view similar to FIG. 3 showing the dial in another position of flight.

FIG. 5 is a view similar to FIG. 1 showing the dial in still another position of flight.

FIG. 6 is a view similar to FIG. 5 showing the dial in another position of flight.

FIG. 7 is a vertical cross-sectional view taken through the center of FIG. 1.

In FIGS. 3, 4 and 5 corner portions have been broken away for convenience of illustration.

The broken line portions in FIG. 7 are for illustrative purposes only.

I claim:

The ornamental design for a two-part attitude indicating aircraft instrument dial, as shown and described.
